CARRIER SYNCHRONIZATION

Teseo Bruno Dante Terroni, Liverpool, England,
assignor to Automatic Telephone & Electric
Company Limited, London, England, a British
company

Application June 24, 1940, Serial No. 342,175
In Great Britain July 4, 1939

8 Claims. (Cl. 250—36)

The present invention relates to carrier telephone and like electrical signalling systems and is more particularly concerned with carrier frequency synchronization arrangements for use therein.

The general object of the invention is to provide a simple and efficient scheme for carrier frequency synchronization between a local and distant terminal or terminals in a system of the above type. The operation of the proposed scheme is substantially independent of variations in line characteristics or of line disturbances which give rise to a detrimental modulation effect in systems involving the use of a pilot frequency for synchronization purposes.

According to the invention an arrangement is provided for maintaining the carrier frequency at a number of stations in synchronism in which variations of the carrier frequency from a given value at one station cause a signal to be transmitted to the other station or stations to cause the frequency of the source of carrier wave oscillations at the other station or stations to be changed accordingly, the signal comprising impulses of current and being dependent upon the relationship between the duration of these impulses and the interval between such pulses, e. g., on and off periods of impulses of current transmitted between the stations. It will be understood of course that it is not essential that no current should flow between pulses provided that such current is quite distinctive. The invention will be better understood from the following description of one method of carrying it into effect reference being had to the accompanying drawings, in which:

Fig. 1 is a schematic view showing the equipment at one station at which one source of oscillations is located.

Figs. 2 and 3 are curves showing the impedance of one and two piezo crystals respectively with respect to frequency for enabling an increased response to be obtained to slight variations of frequency of the source of oscillations in Fig. 1.

Fig. 4 is another schematic view showing the equipment at a second station including a second source of oscillations together with means responsive to variations of frequency of the source of oscillations in Fig. 1 to maintain the two sources of oscillations in synchronism.

Fig. 5 is a schematic view showing in greater detail the photo-telemetering equipment.

For the purpose of this description it will be assumed that a carrier frequency system is in operation over a line between two terminal stations AS and BS. The various carrier frequencies at these stations will be derived from a common source by processes of frequency division and multiplication in well-known manner, the

common source at the master or control station being preferably under crystal control so that the variation of the synchronous carrier frequencies will be very small.

5. According to the invention at the control station AS a selected carrier frequency is arranged to control the movement of the pointer of a meter TM from a central position, that is to say the meter has a central zero. It will be noted 10 that the controlling arrangement includes the source of oscillations OSC1 which feeds two parallel paths, one including the primary winding of the transformer T1 and a piezo crystal C while the other branch includes the primary winding 15 of a transformer T2 and a resistance R1. Preferably the resistance R1 is made of material whose resistance does not vary with temperature and in addition both the resistance and the piezo crystal would preferably be located in a 20 temperature controlled oven. The secondary windings of the two transformers T1 and T2 are connected to full wave rectifiers consisting of unit rectifiers MRA—MRD and MRE—MRH respectively, the output from these rectifiers being connected in parallel to the direct current measuring instrument TM. It will be noted that the unit rectifiers MRA to MRD are connected in the 25 opposite direction to the unit rectifiers MRE—MRH so that when the currents passing through the secondary windings of the transformers T1 and T2 are equal no current will pass through the instrument TM. If, however, the currents differ then the needle of the instrument TM will move to the right or left according as to 30 which is the greater. The crystal C is chosen to have a frequency of resonance which is close to but not identical with the carrier frequency of the source of oscillations OSC1. The impedance curve of the crystal C is shown in Figure 2 35 in full line while the dotted line indicates the frequency of the carrier oscillations generated by OSC1 which it will be noted cuts the full line curve at the point P on the steep slope where the impedance changes rapidly for slight changes 40 in frequency. Normally the resistance R1 is adjusted so as to have substantially the same impedance as the crystal C at the point P which represents the frequency it is desired to maintain. It will thus be appreciated that if the 45 frequency of the source of oscillations should change slightly the impedance of the crystal C will also change quite considerably in proportion and therefore the normal balance of the secondary windings of the transformers T1 and T2 will 50 be disturbed and the needle of the instrument TM will move to the right or left. In place of the resistance R1 a second crystal may be provided having an impedance frequency characteristic represented by the full line curve to the left 55 in Fig. 3, the full line curve to the right corre-

sponding to the curve of the crystal shown in Figure 2, from which it will be noted that the impedances of the crystals change in opposite directions for variations of frequency and therefore increase the difference between the output of the transformers T1 and T2. The rectangle below the meter TM in Fig. 1 represents photo-telemetering equipment PTE and generally corresponds to the transmitting apparatus described in connection with the remote control of meter readings as described in patent specification No. 2,176,720. In these arrangements as far as they concern the present invention the meter scale is continuously scanned by a beam of light which is reflected back on to a photo-cell. The photo-cell in turn preferably controls an oscillator in the case of an alternating current signal and when the meter pointer is on the mid-scale zero position the impulses sent out over the line L to the distant station will have the ratio of the break period to make period equal to one. If the meter pointer is deflected from the centre or zero position then the ratio of the make and break period will be varied in accordance with the signal it is required to transmit. As described the impulses take the form of impulses of carrier current although it will be understood that the invention is not limited to this form of transmission as they could be impulses of voice frequency current or even impulses of direct current. At the distant station the signals pass through a filter F to an amplifier A the output of which leads to the grid circuit of a detector D by which the pulses of carrier frequency are converted into direct current pulses. In the cathode anode circuit either on the cathode or anode side of the high tension source a heavily damped meter movement RM is provided so that normally this meter would tend to take up a reading under the influence of this winding acting alone corresponding to the signal being transmitted as described in the prior specification above referred to but in this case the meter RM is provided with two windings and in order to increase the damping effect both these windings are shunted by a large capacity condenser represented by EC1 and EC2 respectively preferably of the electrolytic type. The second winding of the meter RM is normally fed with direct current from the source of oscillations provided at the station BS from which the various carrier frequencies used at that station are derived. The oscillator OSC2 which is designed to generate oscillations having the same frequency as those generated by OSC1 and is of constant power feeds the primary winding of a transformer T3 via the crystal C2 which is arranged to have a frequency impedance characteristic similar to the impedance frequency characteristic shown in Figure 2, that is to say crystal C corresponds to crystal C of Figure 1. The secondary of the transformer T3 feeds a full wave rectifier represented by the unit rectifiers MRJ to MRM to cause a direct current to flow through the second winding of the magnet RM in such a direction as to oppose the effect on the first winding of the current received over the line L. If the oscillator OSC1 is generating at the correct frequency then the impulse ratio of the make and break periods of the impulses transmitted over the line L will be equal to one and the current generated in the left hand winding of RM will be of such a value as to be exactly equal in its resultant effect due to damping to the effect of the current received from the oscillator OSC2 by the right hand wind-

ing with the result that the pointer of the meter RM takes up a central or zero position. The pointer RM is mechanically connected to a tuning condenser TC which is incorporated in the tuned circuit by which the frequency of the oscillations generated by the oscillator OSC2 is determined. If the source of oscillations at OSC1 varies slightly either up or down then the needle of the meter TM will move to the right or left and the ratio of the make to the break period of the impulse transmitted over the line will either become greater or less than 1, that is to say the net effect of the impulses received by the left-hand winding of the meter RM will rise or fall respectively and consequently the pointer of the meter will move so as to alter the tuning means controlling the oscillator OSC2 so that it now generates a different frequency to cause a current to be generated in the right-hand winding of RM to have an effect relative to the current in the left-hand winding to ensure that the pointer is maintained at a position at which the frequencies generated by OSC1 and OSC2 are equal. It may be that the frequency at the originating station remains constant, that is to say the frequency of the oscillator OSC1, while the frequency of the oscillator OSC2 at the station BS varies. In this case the effect of such a variation will be to cause the current through the right-hand winding to vary while the effect of the current in the left-hand winding remains constant. The pointer will therefore move and the tuning condenser TC be changed to bring the frequency of the oscillator OSC2 back. It will thus be seen that by means of the invention a very satisfactory method which is independent of line variations has been evolved for controlling the frequencies at two stations and it will be readily appreciated that the invention is applicable to more stations by linking them together with similar arrangements, that is to say, the oscillator at station A could control other stations over other lines or other channels or the oscillator at B could control the frequency at another station in a similar way to which B has been controlled by A. It is to be noted that the receiver RM must have its pointer such that when the two currents in the right and left-hand windings respectively balance, that is to say their effects balance, then the pointer must stay in that position as that is the adjustment for correct frequency. The meter therefore in this condition would have no force exerted on it tending to make the pointer move and therefore it is important that there should be no or very little restoring force. The instrument for this purpose would therefore be constructed on the flux-meter or similar principle. In an alternative arrangement instead of employing an indicating instrument an energy meter might be provided in which the effect of the current coil is represented by the unbalance of current obtained from the distant station and from the local source. For instance the current coil could have two windings in opposition one of which was connected to receive the impulses from the distant station and the other of which was connected to receive the rectified current from the local source of oscillations OSC2. The spindle of the meter in this case would be connected to a tuning condenser so that a change of frequency at either the sending or receiving ends would cause the vane to rotate until the change of frequency produced synchronism. When this occurs the effects of the two currents

will balance and the spindle of the meter will remain stationary. The potential coil of the energy meter could be excited from any suitable source of potential.

In another alternative in place of a meter movement as shown in Figure 4 the resultant effect of the impulses transmitted over the line and current derived from the local source might be arranged to control a gas discharge valve which in turn would control a small motor to rotate the tuning condenser until the out of balance is reduced to zero. In a further alternative in which the meter movement is also dispensed with, the out of balance of the two direct currents derived from the transmitted impulses and from the local source of oscillations at station B could be arranged to operate on an iron cored oscillator tuning coil in such a way as to directly vary the frequency in the direction required.

The arrangement according to the invention for correcting frequency changes might be used in conjunction with an arrangement dependent upon the actual value of the frequencies at the two ends so that one would either serve as a check on the other or the combined effect would produce a very fine degree of synchronization. It will be appreciated that the invention may be carried into effect in several ways and is not to be considered as limited to any precise form of receiving equipment or to the utilisation by itself of signals characterised by the ratio of the duration of two distinctive periods of impulses, as such an arrangement could be used in conjunction with other matters, for instance the amplitude of the impulses transmitted over the line might be constant or they might be constant in amplitude while varying as regards the on and off period or they might both vary as regards the on and off periods and in strength provided that they both acted to produce the desired effect in the same direction.

It will be understood that although a quartz crystal has been shown for controlling the frequency deviation as this gives a very satisfactory way of obtaining this result, it will be possible at low frequencies to make use of a high quality resonance circuit made up of inductance coils and condensers.

I claim:

1. An arrangement for maintaining synchronism between sources of oscillations located at different stations, comprising a source of oscillations at one station, means for deriving from said source current impulses having a variable ratio of make and break in dependence upon the frequency thereof, means for transmitting the said impulses to a distant station, a second source of impulses at said distant station, means for deriving a variable direct current from said second source in dependence upon the frequency thereof, responding means at the distant station which in response to impulses received causes a direct current to be generated corresponding to the ratio of the make to break periods of said impulses, and a variably responsive device controlled differentially by the direct current from said responding means, and a variable direct current derived from said second source to control the frequency of said second source in order to maintain the oscillations of said two sources in synchronism.

2. An arrangement for maintaining synchronism between sources of oscillations located at different stations comprising a source of oscillations at one station, means for deriving a

variable direct current from said source in dependence upon the frequency thereof, a direct current ammeter to which said variable direct current is applied, means for transmitting current impulses having the ratio of make and break controlled by the setting of said ammeter to a distant station, a second source of oscillations at said distant station, means for deriving a variable direct current from said second source in dependence upon the frequency thereof, a device controlled jointly by said impulses and said derived variable direct current to control the frequency of said second source in order to maintain the oscillations of said two sources in synchronism.

3. An arrangement for maintaining synchronism between sources of oscillations located at different stations comprising a source of oscillations at one station, a tuning device having a frequency slightly different to the frequency of said source of oscillations, means for deriving a variable direct current from said source controlled by said tuning device in dependence upon the variation of frequency of the source with respect to the frequency of the tuning arrangement, means for transmitting said variable direct current to a distant station, a second source of oscillations at said distant station, a second tuning device having a frequency slightly different to the frequency of said second source of oscillations, means for deriving a variable direct current from said second source controlled by said second tuning device in dependence upon the variation of frequency of the second source with respect to the frequency of the second tuning arrangement, and a device controlled jointly by said derived variable direct currents to control the frequency of said second source in order to maintain the oscillations of said two sources in synchronism.

4. An arrangement for maintaining synchronism between sources of oscillations located at different stations comprising a source of oscillations at one station, a piezo crystal having a frequency slightly different to the frequency of said source of oscillations, means for deriving a variable direct current from said source controlled by said piezo crystal in dependence upon the variation of frequency of the source with respect to the frequency of the piezo crystal, means for transmitting said variable direct current to a distant station, a second source of oscillations at said distant station, a second piezo crystal having a frequency slightly different to the frequency of said second source of oscillations, means for deriving a variable direct current from said second source controlled by said second piezo crystal in dependence upon the variation of frequency of the second source with respect to the frequency of the second piezo crystal, and a device controlled jointly by said derived variable direct currents to control the frequency of said second source in order to maintain the oscillations of said two sources in synchronism.

5. An arrangement for maintaining synchronism between sources of oscillations located at different stations comprising a source of oscillations at one station, a piezo crystal having a frequency slightly different to the frequency of said source of oscillations, a circuit including said piezo crystal and said source of oscillations, a second circuit balanced against said first circuit and including said second source of oscillations and an impedance device means for deriving direct current from each of said circuits an output.

circuit to which direct current derived from said circuits is fed in dependence upon the difference of currents in said circuits, means for transmitting a variable direct current derived from current in said output circuit to a distant station, a second source of oscillations at said distant station, a second piezo crystal having a frequency slightly different to the frequency of said second source of oscillation, means for deriving a variable direct current from said second source controlled by said second piezo crystal in dependence upon the variation of frequency of the second source with respect to the frequency of the second piezo crystal and a device controlled jointly by said derived variable direct currents to control the frequency of said second source in order to maintain the oscillations of said two sources in synchronism.

6. An arrangement for maintaining synchronism between sources of oscillations located at different stations comprising a source of oscillations at one station, a piezo crystal having a frequency slightly different to the frequency of said source of oscillations, a circuit including said piezo crystal and said source of oscillations, an impedance device, a second circuit including said source of oscillation and said impedance device, means for deriving a direct current from each of said circuits, a circuit in which the direct currents derived from said circuits act in opposition, an ammeter in said circuit variably controlled by the out of balance currents created by a variation of frequency of the source with respect to the frequency of the piezo crystal, an alternating current impulse generator controlled by said ammeter to vary the ratio of make and break periods of impulses generated in accordance with the reading thereof as determined by a light scanning arrangement, means for transmitting said impulses of alternating current to a distant station, means for rectifying said impulses of alternating current at the distant station, a heavily damped meter movement having two exciting windings, one of said windings being excited by said rectified impulses, a second source of oscillations at said distant station a second piezo crystal having a frequency slightly different to the frequency of said second source of oscillations and in circuit therewith means for deriving a variable direct current from said circuit in dependence upon the variation of frequency of the second source with respect to the frequency of the second piezo crystal, a circuit enabling said variable direct current to be fed to the second winding of said heavily damped meter movement, and tuning means controlled by said meter movement for adjusting the frequency of said second source of oscillations whereby the frequency of the two sources may be maintained in synchronism.

7. An arrangement for maintaining synchronism between sources of oscillations located at different stations comprising a source of oscillations at one station, a piezo crystal having a frequency slightly below the frequency of said source of oscillations, a circuit including said piezo crystal and said source of oscillations, a second piezo crystal having a frequency slightly above the frequency of said source of oscillations a second circuit including said source of oscillation and said second piezo crystal means for deriving a direct current from each of said circuits, a circuit in which the direct currents de-

rived from said circuits act in opposition an ammeter in said circuit variably controlled by the out of balance currents created by a variation of frequency of the source with respect to the frequency of the piezo crystals an alternating current impulse generator controlled by said ammeter to vary the ratio of make and break periods of impulses generated in accordance with the reading thereof as determined by a light scanning arrangement, means for transmitting said impulses of alternating current to a distant station, means for rectifying said impulses of alternating current at the distant station, a heavily damped meter movement having two exciting windings, one of said windings being excited by said rectified impulses, a second source of oscillations at said distant station a third piezo crystal having a frequency slightly different to the frequency of said second source of oscillation and in circuit therewith means for deriving a variable direct current from said circuit in dependence upon the variation of frequency of the second source with respect to the frequency of the third piezo crystal, a circuit enabling said variable direct current to be fed to the second winding of said heavily damped meter movement, and tuning means controlled by said meter movement for adjusting the frequency of said second source of oscillations whereby the frequency of the two sources may be maintained in synchronism.

8. An arrangement for maintaining synchronism between sources of oscillations located at different stations comprising a source of oscillations at one station, a piezo crystal having a frequency slightly different to the frequency of said source of oscillations, a circuit including said piezo crystal and said source of oscillations, an impedance device a second circuit including said source of oscillation and said impedance device means for deriving a direct current from each of said circuits, a circuit in which the direct currents derived from said circuits act in opposition an ammeter in said circuit variably controlled by the out of balance currents created by a variation of frequency of the source with respect to the frequency of the piezo crystal an alternating current impulse generator controlled by said ammeter to vary the ratio of make and break periods of impulses generated in accordance with the reading thereof as determined by a light scanning arrangement, means for transmitting said impulses of alternating current to a distant station, means for rectifying said impulses of alternating current at the distant station, an electromagnetic device having two exciting windings, one of said windings being excited by said rectified impulses, a second source of oscillations at said distant station, a second piezo crystal having a frequency slightly different to the frequency of said second source of oscillations and in circuit therewith means for deriving a variable direct current from said circuit in dependence upon the variation of frequency of the second source with respect to the frequency of the second piezo crystal, a circuit enabling said variable direct current to be fed to the second winding of said electromagnetic device, and tuning means controlled by said electromagnetic device for adjusting the frequency of said second source of oscillations whereby the frequency of the two sources may be maintained in synchronism.
